United States Patent Office

Des. 229,754
Patented Jan. 1, 1974

229,754

AIR FRESHENER

James V. Ali, 2646 Richmar Drive,
Xenia, Ohio 45385

Filed Dec. 4, 1972, Ser. No. 311,862

Term of patent 14 years

Int. Cl. D23—04; D11—04
U.S. Cl. D23—150

FIG. 3

FIG. 4

FIG. 1 is a top perspective view of an air freshener showing my new design;

FIG. 2 is a bottom perspective view thereof;

FIG. 3 is a side elevational view thereof on a reduced scale;

FIG. 4 is a top plan view thereof on a reduced scale.
I claim:

The ornamental design for an air freshener, as shown and described.
